UNITED STATES PATENT OFFICE.

JOHN WILLIAM MUNTZ, OF HOLGATE, OHIO.

BLOWER.

1,385,261.

Specification of Letters Patent. Patented July 19, 1921.

Application filed July 29, 1919. Serial No. 314,120.

To all whom it may concern:

Be it known that I, JOHN W. MUNTZ, a citizen of the United States, residing at Holgate, in the county of Henry and State of Ohio, have invented certain new and useful Improvements in Blowers; and I do hereby declare the following to be a full, clear, and exact description of the invention, such as will enable others skilled in the art to which it appertains to make and use the same.

This invention relates to grain stackers or elevators and the primary object of the invention is to provide an improved means for elevating grain from the thresher to the bins in the grainery.

Another object of the invention is to provide an improved pneumatic grain elevator, which is so constructed that grain can be effectively elevated a considerable height.

20 A further object of the invention is to provide an improved pneumatic grain elevator, which can be readily carried from one place to another, and taken apart when desired.

25 A further object of the invention is to provide an improved pneumatic grain stacker embodying a pair of fans operatively connected together, one of which is adapted to take the grain from the hopper and throw the same upwardly, and the other being adapted to throw a strong stream of air into the grain, at a point above the first fan.

30 A further object of the invention is to provide an improved pneumatic grain stacker having a novel form of elbow connection for conveying the grain to the bin, so as to effectively guide the stream of air, so that the full effect of the same will be transmitted to the grain.

35 A still further object of the invention is to provide an improved device of the above character, which is durable and efficient in use, one that is simple and easy to manufacture, and one that can be placed upon the market at a reasonable cost.

40 With these and other objects in view, the invention consists in the novel construction, arrangement and formation of parts, as will be hereinafter more specifically described, claimed and illustrated in the accompanying drawings, forming a part thereof, in which:

45 Figure 1 is a side elevation of the improved stacker,

Fig. 2 is an end elevation of the improved

Fig. 3 is a vertical longitudinal section taken on the line 3—3 of Fig. 2,

Fig. 4 is a detail vertical section through the fans, and

Fig. 5 is a detail view of the elbow connection for connecting the vertical portion of the conveyer pipe to the horizontal portion.

Referring to the drawings in detail, wherein similar reference characters designate corresponding parts throughout the several views, the numeral 1 generally indicates the improved pneumatic grain elevator, which includes the supporting frame 2, and the blowers 3.

The supporting frame 2 is formed relatively large, so as to form a substantial base for the blower and thus prevent the same from tipping over while in operation. The frame 2 includes the longitudinally extending side bars 5, having the reduced ends 6 forming handles whereby the same may be readily grasped and carried from one place to the other. The longitudinally extending bars 5 are provided adjacent each end with vertically extending recesses 7, which are adapted to receive stakes or the like so that the same can be securely fastened to the ground and thus prevented from accidental displacement. The longitudinally extending bars 5 are connected by the transverse bars 8 and the transverse and longitudinal bars are securely bolted together as at 9.

90 The blower 3 includes the casing 10, having the side plates or walls 11 and the front and rear walls 12 and 13, which are preferably formed from a single strip of material bent to conform to the configuration of the side edges of the side plates and held thereto by means of bolts 14. The casing is provided with transverse curved partitions 15 and 16, which divide the same into substantially circular fan casings 17 and 18. The upper fan casing 18 is located slightly in advance of the lower fan casing 17 and the upper casing is provided with bearings 19 for rotatably receiving the shaft 20 which protrudes outwardly from one end thereof and has keyed thereto the drive pulley 21 which is adapted to be connected by a suitable belt to any preferred type of prime mover, not shown. The outwardly extending end of the drive shaft 20 is received in a

journal 22 carried by the upstanding standard 23, which is secured by bolts 24 to the central portion of the inner surface 1 of the longitudinally extending bars 5. The drive shaft 20 has secured thereto a fan wheel 25, which includes the hub 26 having the tangentially extending arms 27 to which are bolted the blades 28. The fan casing is provided with an upstanding outlet 29, which is divided from the outlet 30 of the lower fan casing 17 by means of a central partition 31. As clearly shown in Fig. 3 of the drawings, the outlets converge at their upper ends so that the blast of air from the fan 25 will meet with the air current from the lower fan. The casing 3 is held against accidental displacement by suitable substantially inverted U-shaped braces 32 which are bolted at their lower ends, as at 33, to the frame, and at their upper ends to the side plates 11. The braces are located on each side of the casing 3 and prevent relative lateral movement of the casing in relation to the frame. As shown, the lower end of the casing fits directly in the frame between the longitudinally extending bars 5. The casing is further held against movement by inclined braces 34 which have their lower ends bolted to the longitudinally extending bars 35 and to outwardly extending ears 36 formed on the casing adjacent to the upper end thereof. The lower fan casing 17 has journaled to one wall thereof the shafts 37 which has keyed thereto the lower wheel 38 which includes the substantially conical shaped hub 39 carried by the side disk 40 which has a plurality of arcuate shaped blades 41 secured thereto, which extend inwardly from the outer edge of the disk toward the center and short of the hub 39. The inner ends of the blades are connected by the annular side wall 42. The lower fan casing 17 is provided with an enlarged opening 42^a which communicates with the open portion of the cylindrical wall 41 for permitting the grain from the hopper 43 to flow into the same. The shaft 37 protrudes outwardly from the opposite wall of the casing 17 through the opening 42^a and has keyed thereto the pulley 43^a around which is trained the belt 44. The belt 44 is trained around the upper pulley 45 which is keyed to the drive shaft 20. Thus, upon rotation of the drive shaft, the upper fan 25 is rotated, as well as the lower fan 38.

The hopper 43 is detachably connected to the frame and includes the vertical front wall 46 and the inclined rear wall 47 and the downwardly inclined side walls 48. The lower ends of the end walls 48 and the rear wall 47 are connected by the inclined bottom wall 48 which serves to direct the flow of grain from the hopper into the lower fan casing and the front wall 46 of the hopper 65 is provided with an opening 49 which is

adapted to register with the opening in the casing 17. A cleat 50 is secured to the lower end of the rear wall 47 and is adapted to engage the rear longitudinal bar 5 so as to hold the hopper against displacement. 70

In operation of the improved device, the grain to be elevated is placed in the bin and owing to the inclined sides thereof grain is directed into the lower casing 17 where the same is caught by the rotating wheel 38 and thrown upwardly out of the outlet 30 where the same is met by the blast of air from the fan 26, which elevates the same to the desired height. 75

The outlets 29 and 30 of the upper and lower fans converge, as stated, into a tubular extension 51, which receives the pipe 52, which may be made in any number of sections so that the grain can be elevated to the desired height. The upper end of the pipe 2 has connected thereto a novel form of elbow coupling 53, which is curved forwardly as at 54 and then downwardly as at 55 and terminates in a reduced horizontal portion 56 to which may be secured the branch pipes for conveying the grain to the desired bins. 80

The downwardly and then forwardly curved portions 55 and 56 of the elbow connection 53 serve to allow the blast of air 95 to act fully upon the grain in the branch pipe. As the blast of air comes up the pipe 52, the same strikes the turn 54 in the elbow and is deflected downwardly striking the forward turn 55 of the pipe and then directed into the branch pipe. 100

An opening 57 is formed in the rear wall of the casing located intermediate the fans so that the grain can be let out of said opening in case the grain is fed into the fan too fast, before the machine has reached full speed. This opening is closed by a door 58, which is pivoted intermediate its ends, as at 58^a, on one of the bolts which hold the sides of the casing in place. The door 58 also forms a valve to prevent the grain from being thrown up into the outlet too fast and has a weight 59 secured thereto, so as to normally hold the same closed. The valve can be regulated so as to control the 115 flow of the grain through the outlet. 105

An idle pulley 60 is journaled on a shaft 61, which is pivotally secured to the casing as at 62, and the pulley is normally held into engagement with the belt 44 by means of 120 the spring 63 coiled around the regulating rod 64 adjustably carried by an ear 65 extending outwardly from the casing. 110

From the foregoing description, it can be seen that an improved pneumatic elevator 125 is provided for grain, which will effectively raise the grain to the desired height.

In practice, I have found that the form of my invention illustrated in the accompanying drawings and referred to in the 130

above description, as the preferred embodiment, is the most efficient and practical; yet realizing the conditions concurrent with the adoption of my device will necessarily vary,

5 I desire to emphasize that various minor changes in details of construction, proportion and arrangement of parts may be resorted to, when required without sacrificing any of the advantages of my invention as

10 set forth.

What I claim as new is:

1. A pneumatic appliance of the character specified comprising a fan blower, a conduit in communication with the fan blower 15 and having a lateral opening, and a valve pivoted at one side of the conduit in line with the opening thereof and extending across the conduit at a relatively upwardly and forwardly inclination.

20 2. A pneumatic appliance of the character specified comprising a fan blower, a conduit in communication with the fan blower and

having a lateral opening, a bolt positioned in the opening, and a valve pivoted on the bolt and extending across the conduit at an 25 inclination and automatic in its action.

3. A pneumatic appliance of the character specified comprising relatively upper and lower fan blowers, a hopper at one side of the fan blowers and discharging into the 30 lower fan blower casing, a conduit common to the casings of both fan blowers, a longitudinal partition dividing the conduit into independent passages, the outer passage having a lateral opening, and a valve extending 35 through the lateral opening at an inclination and pivoted to the conduit.

In testimony whereof I affix my signature in presence of two witnesses.

JOHN WILLIAM MUNTZ.

Witnesses:

HERMAN H. MEYER,
FRANK J. HOHENBRINK.
